CLAIM

We claim the ornamental design for a spa tray with light, as shown and described.

DESCRIPTION

FIG. 1 is an outer, top perspective view of a spa tray with light showing our new design in an environment of use; FIG. 2 is an inner, top perspective view thereof; FIG. 3 is an outer, top perspective view of the spa tray with light, shown removed from the environment for clarity of disclosure;

FIG. 4 is an inner elevational view thereof;

FIG. 5 is an outer elevational view thereof;

FIG. 6 is a right side elevational view thereof;

FIG. 7 is a left side elevational view thereof;

FIG. 8 is a top plan view thereof; and,

FIG. 9 is a bottom plan view thereof.

The broken lines in the drawings depict portions of the spa tray with light that form no part of the claimed design. The additional broken lines in FIGS. 1-2 showing a spa depict environment only and form no part thereof.
